(57) **CLAIM**

The ornamental design for a "pharmaceutical packaging," as shown and described.

DESCRIPTION

FIG. 1 is a top, front and right side perspective view of a pharmaceutical packaging according to our design; FIG. 2 is a front elevational view thereof; FIG. 3 is a rear elevational view thereof; FIG. 4 is a right side elevational view thereof; FIG. 5 is a left side elevational view thereof; FIG. 6 is a top plan view thereof; FIG. 7 is a bottom plan view thereof; FIG. 8 is an elevational view of the internal wall surfaces of the pharmaceutical packaging in an unfolded condition; and, FIG. 9 is an elevational view of the external wall surfaces of the pharmaceutical packaging in an unfolded condition. The broken lines shown in FIGS. 3 and 9 represent perforation lines.
